Primary Examiner — David G Muller*(74) Attorney, Agent, or Firm* — Birch, Stewart, Kolasch & Birch LLP(57) **CLAIM**

The ornamental design for an operating grip for endoscope, as shown and described.

DESCRIPTION

FIG. 1 is a top, front and left side perspective view of an operating grip for endoscope showing my new design; FIG. 2 is a top, rear and left side perspective view thereof; FIG. 3 is a top, front and right side perspective view thereof; FIG. 4 is a bottom, front and left side perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a left side elevational view thereof; and,

FIG. 10 is a right side elevational view thereof.

The broken lines showing the portions of the operating grip for endoscope in all views shown represent unclaimed subject matter and form no part of the claimed design.
